DESIGN FOR A COAT

Israel Yellin, New York, N. Y.

Application July 11, 1936, Serial No. 63,772

Term of patent 3½ years

To all whom it may concern:

Be it known that I, Israel Yellin, a citizen of the United States of America, residing in Manhattan, county of New York, and State of New York, have invented a new, original, and ornamental Design for a Coat, of which the following is a specification, reference being had to the accompanying drawing, forming part thereof, wherein,

The characteristic feature of my design resides in the two piece overlocking envelope collar, as shown in combination with the coat.

I claim:

The ornamental design for a coat, substantially as shown and described.

ISRAEL YELLIN.
